TYPOGRAPHICAL COMPOSING MACHINE

Harold A. Burt, St. Albans, N. Y., assignor to
Mergenthaler Linotype Company, a corpora-
tion of New York

Application May 12, 1932. Serial No. 610,765

20 Claims. (Cl. 199—20)

This invention relates to typographical com-
posing machines, such as line casting machines
of the general organization represented in U. S.
Letters Patent to O. Mergenthaler, No. 436,532,
5 wherein matrices are released by key-controlled
escapements from a magazine in which they are
stored and then composed in line, the composed
line transferred to the face of a slotted mold for
the casting of a type bar or slug, and the matrices
10 thereafter returned through distributing mech-
anism to the magazine from which they started.

In some machines, the matrix releasing es-
capements are carried by the magazine, being
removed with the latter when a change is made
15 from one font to another, while in other ma-
chines, the escapements are supported independ-
ently of the magazine so as to remain permanent-
ly in the machine and cooperate with different
magazines as the latter are interchanged. As a
20 result, two different classes of machines have
come into use, one designed for magazines with
escapements, and the other for magazines with-
out escapements. Machines sold under the name
"Intertype" fall wholly within the first class,
25 and machines sold under the name "Linotype"
fall partly within the second class. As these dif-
ferent classes of machines are now constructed,
the matrix magazines are not interchangeable,
that is to say, for example, an Intertype maga-
30 zine cannot be used in a Linotype machine, nor
can a Linotype magazine be used in an Intertype
machine. This of course is a serious drawback
to the user.

The present invention aims to remove the fore-
35 going disability and contemplates certain im-
provements whereby magazines with or without
escapements may be used interchangeably in
the same machine with perfect freedom. In the
present instance, the improvements have been
40 shown as embodied in a machine of the Lino-
type class, but it is obvious that they could be
embodied equally as well in a machine of the In-
tertype class; and moreover, they have herein
been evolved specifically so that a Linotype ma-
45 chine may be equipped either with a Linotype
magazine (which is devoid of escapements), or
with an Intertype magazine (which carries its
own escapements), but here again it is obvious
that the same scheme would apply to magazines
50 of other kinds, as for example, to Linotype maga-
zines alone, some carrying escapements and oth-
ers devoid of escapements.

In carrying out the invention (herein shown
as applied to a machine of the Linotype Model
55 8 variety), the base frames whereon the maga-

zines are removably supported are each equipped
with a bank of escapements to cooperate in the
regular way with the standard form of Linotype
magazine having no escapements and also with
a bank of escapement actuating elements ar-
60 ranged to cooperate directly with the escape-
ments carried by the standard form of Intertype
magazine. In the present embodiment, each
escapement bank is pivoted to its base frame so
as to be capable of being swung into or out of
65 operative relation to the escapement actuating
elements, which latter are mounted fixedly in
the base frame.

According to the foregoing arrangement,
when any given base frame is to be equipped
70 with a Linotype magazine, the escapement bank
is swung into operative relation to the actuating
elements and in that position will cooperate di-
rectly with the magazine, just as it does in the
commercial Linotype machine. On the other 75
hand, when any given base frame is to be equipped
with an Intertype magazine, the es-
capement bank is swung out of operative rela-
tion to the actuating elements, which latter are
then free to engage directly with the escape-
80 ments carried by that magazine. In either case,
the escapement actuating elements are called
into play, being operated by the regular key-con-
trolled power-operated devices embodied in the
standard or commercial Linotype machine. 85

Other improvements have been made in adapt-
ing the Linotype machine to handle either Lino-
type or Intertype magazines, but these improve-
ments will best be understood from the detailed
description to follow. 90

Referring to the drawings:

Fig. 1 is a side elevation of a Linotype machine
equipped with the present improvements;

Fig. 2 is an enlarged vertical section taken
through the lower part of the magazines and the 95
assembler entrance;

Fig. 3 is a cross section taken on the line 3—3
of Fig. 2 looking in the direction of the arrows;

Fig. 4 is a vertical cross section taken through
a Linotype magazine and the guideway in which 100
it is slidably mounted;

Fig. 5 is a similar cross section taken through an
Intertype magazine and showing the guideway as
modified to correspond;

Fig. 6 is a plan view taken on the line 6—6 of 105
Fig. 2;

Fig. 7 is an enlarged plan view taken on the
line 7—7 of Fig. 2;

Fig. 8 is a diagrammatic view illustrating the
angle of a groove in the guide member interposed 110

between the assembler entrance and the magazines; and

Fig. 9 is a plan view of one of the base frames detached and showing the escapement bank in operative relation to the escapement actuating elements.

As before stated, the invention has been shown herein as applied to a machine of the Linotype Model 8 variety, which machine comprises a shift frame composed of three pivoted base frames A upon which the different magazines are removably mounted. The shift frame is arranged to be raised and lowered in the usual way to bring any selected one of the magazines into operative relation to the fixed assembler entrance B. If further information in regard to the shift frame is desired, reference may be had to the McNamara Patent No. 1,536,316, dated May 25, 1926, or to the commercial Linotype machine now in extensive use.

In Fig. 1, the top and bottom magazines C represent the standard form of Intertype magazine, while the middle magazine D represents a standard form of Linotype magazine, sometimes known as the "Model 5 magazine". As more clearly shown in Fig. 2, each Intertype magazine C carries its own bank of escapements C¹, these being of the form shown and described in the Homans Patent No. 1,092,715, dated April 7, 1914, while the Linotype magazine D is devoid of escapements, being grooved on its underside to receive a bank of escapements D¹ mounted on the base frame. These escapements D¹ are quite similar to the escapements employed in the commercial Linotype machines, or as illustrated in the Rogers Patent No. 1,109,872, dated September 8, 1914, differing therefrom mainly as to mounting and manner of operation, as will now be described.

According to the present invention, the escapements D¹ are mounted in a supporting bar or frame E pivoted or hinged to the base frame at E¹, whereby the escapements may be swung as a unit through an angle of about 180° either into an inoperative position as shown in connection with the upper base frame in Fig. 2 (see also Fig. 6), or into an operative position as shown in connection with the lower base frame in Fig. 2, (see also Fig. 9). In the former or inoperative position, the escapement unit lies entirely below the upper face of the base frame and will therefore stand clear of an Intertype magazine supported thereon, whereas in the latter or operative position, the escapement unit presents the escapements proper in position to enter the underside of a Linotype magazine supported on the frame. It may here be stated that the escapement bar E, when in its inoperative position, is supported at its free corners by lugs E² on the base frame, these lugs being provided with spring buffers or cushions E³. In its operative position, the escapement bar merely rests upon an underlying bar or frame F which carries the escapement actuating elements, the meeting faces of the bars E and F being flat and accurately machined to insure the proper functioning of the parts.

The supporting bar F, unlike the escapement bar E, is fixedly mounted in the base frame, being rigidly though detachably secured thereto by means of screws F¹ or similar fastening devices. The escapement actuating elements comprise a series of vertically movable pawls H pivoted to the free ends of rocker arms or levers H¹ mounted to turn on a fixed rod or pivot H² secured to the bar F, it being understood that there are as many such pawls and levers as there are individual

escapements in the different banks C¹ and D¹. Guide plates H³ separate the pawls and levers from one another in the manner of the guide plates commonly associated with the escapements. Directly below the pivot H², the rocker arms H¹ are formed with laterally projecting lugs H⁴ which are arranged to be engaged by push rods H⁵ slideable fore-and-aft in guideways formed on the underside of the bar F.

Parenthetically, it may be stated that these push rods H⁵, in the regular Linotype escapement construction, are arranged to engage with lugs depending directly from the rocker arms or levers of the escapements D¹, but in carrying out the present invention, the push rods are caused to actuate the escapements D¹ when in use through the medium of the pivoted levers H¹ and pawls H (see the lower magazine of Fig. 2, as well as the showing in Fig. 3).

The operation of the parts will now be clear:

In Fig. 2, the upper base frame is shown as supporting an Intertype magazine C, and it will be observed that the tail pieces C² of the escapements C¹ of that magazine are arranged in direct engaging relation to the actuating pawls H, so that when these pawls are raised by the rearward movement of the push rods H⁵, the escapement levers will be reversed in position so as to release the leading matrix in the magazine and to arrest the following matrix in the usual way. The springs C³ will thereafter restore the parts to their original position, permitting the following matrix to become the leading matrix. The escapements C¹, being entirely separate from the escapement actuating pawls H, will not of course interfere with the ready removal of the magazine C from the base frame (see Fig. 1).

The lower base frame in Fig. 2 is shown as supporting a Linotype magazine D, and here it will be observed that the tail pieces D² of the escapements D¹ of that magazine are arranged in direct engaging relation to the actuating pawls H, so that when these pawls are raised by the rearward movement of the push rods H⁵, the escapement levers will be reversed in position so as to release the leading matrix in the magazine and to arrest the following matrix in the usual way, just as in the case of the escapements C¹. The springs D³ will thereafter restore the parts to their original position. Since the escapements D¹ are entirely separate from the magazine D, they will not of course interfere with its removal from the base frame, but they will remain in place to cooperate with another Linotype magazine if one of that kind is substituted, or be movable out of the way, as with the upper base frame, if an Intertype magazine is to be substituted.

Since the Intertype magazines C carry their own escapements, the latter will act to retain the matrices in the magazines when the latter are removed from or replaced in the machine. The Linotype magazines, however, being devoid of escapements, require the use of locking devices to retain the matrices therein during removal or replacement, but since these locking devices are of well-known construction and form no part of the present invention, it is unnecessary to describe them herein, but if desired reference may be had to the McNamara patent before mentioned. It need only be stated here that the supporting block X which carries the magazine latch controlled by the matrix locking bar, instead of being mounted on the escapement bar E, is mounted on the supporting bar F for the escapement actuating elements, this change being resorted

to because the bar F is fixed while the bar E is pivoted.

It hardly needs to be stated that once the machine is fully equipped with magazines, whether 5 of one kind or the other, the shift frame in which they are supported is free to be raised or lowered to bring any selected magazine into operative relation to the fixed assembler entrance B. With the selected magazine in such operative position, the escapement actuating elements of 10 that magazine are operated by the usual key-controlled power-operated devices, including the pivoted levers G (Fig. 1) which are arranged to engage the forward ends of the push rods H⁵.

15 If the magazines C and D were alike, except as to the escapements, no change would be necessary in providing for their support on the base frames A, but since the Intertype and Linotype magazines do differ in some particulars, the following improvements have been made to take 20 care of these differences.

Referring first to the Linotype magazine D, it is formed on its underside, as usual, with a plurality of transverse bars J and a central longitudinal guide bar J¹. When the magazine is supported in place upon the base frame A, the transverse bars J engage behind shoulders L rising therefrom, and during the removal of the magazine from the base frame, the bar J¹ slides 30 in a groove L¹ disposed centrally and longitudinally of the base frame. In the arrangement shown, the shoulders L and groove L¹ are formed upon a lifting plate M normally nested within the base frame and pivoted thereto at the top as at M¹. 35 At the lower or free end of the lifting plate M, there is arranged an operating cam M³ fast to a transverse rock shaft M² which is adapted to be turned by a pair of arms M⁴ such as are used in removing the magazine from the base frame.

40 This arrangement is fully described in the McNamara patent before mentioned and needs no elaboration. The present invention deals only with changes made in the parts to adapt them to handle an Intertype magazine C as well as a 45 Linotype magazine D.

The Intertype magazine C is also formed on its underside with a plurality of transverse bars K and a central longitudinal guide bar K¹. When the magazine is supported in place upon the base 50 frame A, the second transverse bar K from the top will engage a pair of spring actuated latches N, (see lower magazine of Fig. 1). As these latches N are secured to the base frame A and therefore stationary, the transverse bars K will 55 leave engagement when magazine C is lifted for removal. The lifted magazine C will commence to slide down the lifting plate M to be caught by engagement of the relay shoulders L² of the lifting plate M and the second transverse bar K 60 from the bottom. When a Linotype magazine is in use, these latches N will be pushed out of engagement by the corresponding bar J (see middle magazine of Fig. 1).

The central longitudinal bar K¹ of the Intertype magazine is narrower than the corresponding bar J of the Linotype magazine, and hence the groove L¹ could not be relied upon to guide the magazine C properly during its removal. For this reason, and in order to provide a guideway 65 corresponding in width to that of the bar K¹, the base frame A is provided at different points along the length of the groove L¹ with pairs of opposed lugs O disposed in cross cuts or grooves O¹ and pivoted at O². In their retracted or inoperative 70 position (see Fig. 4) the lugs O stand out of the

way, leaving the groove L¹ of full width to cooperate with the bar J¹ of a Linotype magazine D. In their projected or operative position (see Fig. 5) the lugs O stand partly across the groove L¹ and serve to provide a guideway of less width to 80 cooperate with the bar K¹ of an Intertype magazine C.

While the Intertype magazine C is of the same outside dimensions as the Linotype magazine D, the grooved matrix channels of the two magazines differ in spacing and in angularity. The difference in spacing applies only to the upper ends of the magazines, the groove of the Linotype magazine being equally spaced apart to correspond with the equal spacing of the magazine entrance channels and the distributor bar combinations, and the grooves of the Intertype magazine being unequally spaced apart to correspond with the unequal spacing of the magazine entrance channels and the distributor bar combinations. To take care of these differences, it is proposed to equip the machine with interchangeable magazine entrances and interchangeable distributor bars, a suitable arrangement for the purpose being shown and described in the Kennedy Patent No. 1,698,636, dated January 8, 1929, or in applicant's copending application Serial No. 574,116, filed November 10, 1931. Since no claim is being made herein to such an arrangement, further description becomes unnecessary. 95

At the lower ends of the two magazines, the spacing of the grooved channels is substantially the same, but owing to the difference in spacing at the top, it is obvious that the angularity of the grooves will vary in many cases. In both 100 magazines, the grooves converge from the upper end toward the lower delivery end of the magazine, and the angles referred to are the angles of convergence. Because of this difference in the angles of convergence, the matrices in leaving 110 the lower or discharge ends of the magazines take different paths and would in many instances conflict with the partitions or guide plates B¹ of the assembler entrance B. To overcome this difficulty, it is proposed to interpose between the 115 assembler entrance B and the magazines a 120 grooved matrix guide member P, this member in the present instance being attached in a fixed position to the assembler entrance frame so as to cooperate with all the magazines alike. The 125 member could of course be attached to each magazine or base frame, but such a duplication is avoided by mounting it on the assembler entrance frame.

The guide member P is formed with as many 130 grooves P¹ as there are grooved matrix channels in the magazines, and these grooves are arranged to register with and form continuations of the grooves of the particular magazine brought into operative relation to the assembler entrance (see 135 Figs. 2 and 7). Preferably, the grooves P¹ are flared at their upper or receiving ends, as indicated at P². Since the angles of convergence of the corresponding grooves of the two magazines C and D differ, the grooves P are arranged at mean 140 angles or angles intermediate of the two. Thus, referring to Fig. 8, the matrix at the left is shown as approaching the grooved member P along the line R, while the matrix at the right is shown as approaching the grooved member along the line T, these two lines being indicative in an exaggerated way of the difference in the angles of convergence of two corresponding grooved channels of a Linotype magazine C and an Intertype magazine D. The angle of the registering groove 150

P^1 of the member P is indicated by the line S, which it will be observed is the mean of the angles represented by the lines R and T. This difference in angularity will not necessarily apply to 5 all of the grooves of the two magazines, but wherever it does apply, it is proposed to cut the grooves P^1 at a mean angle.

In the accompanying drawings the invention has been shown merely in preferred form and by 10 way of example, but it will be understood that many changes and modifications may be made therein and in its mode of application without departing from the spirit of the invention. It is to be understood, therefore, that the invention 15 is not limited to any specific form or arrangement, except insofar as such limitations are specified in the appended claims.

Having thus described my invention, what I claim is:

20 1. In or for a typographical composing machine adapted to be equipped with matrix magazines with or without matrix releasing escapements, a supporting frame common to both kinds of magazines and provided with a bank of escapements to cooperate with a magazine devoid of escapements and also with a bank of escapement actuating elements to cooperate with a magazine carrying escapements.

25 2. In or for a typographical composing machine adapted to be equipped with matrix magazines with or without matrix releasing escapements, a supporting frame common to both kinds of magazines and provided with a bank of escapements to cooperate with a magazine devoid of escapements and also with a bank of escapement actuating elements to cooperate with a magazine carrying escapements, said bank of escapements being movable into or out of operative relation to the escapement actuating elements 30 according to the magazine selected.

35 3. In or for a typographical composing machine adapted to be equipped with matrix magazines with or without matrix releasing escapements, the combination of a magazine supporting frame, a bank of escapement actuating elements mounted in fixed position upon the frame and arranged to cooperate directly with the escapements of a magazine carrying escapements, and a bank of escapements adapted to be sustained in operative relation to the escapement actuating elements and arranged when so sustained to cooperate directly with a magazine devoid of escapements.

40 4. In or for a typographical composing machine adapted to be equipped with matrix magazines with or without matrix releasing escapements, the combination of a magazine supporting frame, a bank of escapement actuating elements mounted in fixed position upon the frame and arranged to cooperate directly with the escapements of a magazine carrying escapements, and a bank of escapements adapted to be superimposed upon the escapement actuating elements so as to be actuated thereby and arranged in such 45 position to cooperate directly with a magazine devoid of escapements.

45 5. In or for a typographical composing machine adapted to be equipped with matrix magazines with or without matrix releasing escapements, the combination of a magazine supporting frame, a bank of escapement actuating elements mounted in fixed position upon the frame and arranged to cooperate directly with the escapements of a magazine carrying escapements, and a bank of escapements pivoted to the sup-

porting frame and arranged to be swung into and out of operative relation to the escapement actuating elements.

50 6. In or for a typographical composing machine adapted to be equipped with matrix magazines with or without matrix releasing escapements, the combination of a magazine supporting frame, a bank of escapement actuating elements mounted in fixed position upon the frame and arranged to cooperate directly with the escapements of a magazine carrying escapements, and a bank of escapements pivoted to the supporting frame and arranged to be swung into and out of operative relation to the escapement actuating elements, the escapements when in one position permitting the escapement actuating elements to cooperate directly with a magazine carrying escapements and when in its other position to cooperate directly with a magazine devoid of escapements.

55 7. In or for a typographical composing machine, the combination of a matrix magazine carrying a bank of matrix releasing escapements, a supporting frame whereon the magazine is removably mounted, and a bank of escapement actuating elements fixedly mounted on the supporting frame and arranged in operative relation to the escapements.

60 8. In or for a typographical composing machine, the combination of a matrix magazine devoid of escapements, a supporting frame whereon the magazine is removably mounted, a bank of matrix releasing escapements adapted to cooperate with the magazine, and a bank of escapement actuating elements arranged in operative relation to the escapements, said escapements and escapement actuating elements being independently mounted on the supporting frame.

65 9. In or for a typographical composing machine, the combination of a matrix magazine devoid of escapements, a supporting frame whereon the magazine is removably mounted, a bank of matrix releasing escapements adapted to cooperate with the magazine, and a bank of escapement actuating elements arranged in operative relation to the escapements, said escapement actuating elements being fixedly mounted on the supporting frame and said escapements being movably mounted thereon.

70 10. An arrangement according to claim 9, characterized by the fact that the escapement actuating elements comprise series of reciprocating pawls, short pivoted levers carrying the pawls, and push rods for rocking the pivoted levers in one direction.

75 11. In or for a typographical composing machine, the combination of a matrix magazine, a supporting frame whereon the magazine is removably mounted, a bank of matrix releasing escapements mounted on one of said parts and each escapement being provided with a rearward extension, and a bank of escapement actuating elements fixedly mounted on the supporting frame, said elements comprising series of reciprocating pawls arranged to engage the rearward extensions of the escapements, pivoted levers carrying the pawls, and fore-and-aft push rods for rocking the pivoted levers in one direction.

80 12. In or for a typographical composing machine, the combination of two matrix magazines, one carrying escapements and the other devoid of escapements, two base frames whereon the magazines are removably mounted, means for shifting the base frames to bring either selected magazine into operative position, a bank of es-

- capement actuating elements fixedly mounted on each of the base frames, the escapement actuating bank of one frame being arranged in direct engaging relation to the escapements carried by 5 the magazine on that frame, and a bank of escapements sustained by the other frame in operative relation to the escapement actuating elements thereon and arranged to cooperate directly with the magazine carried by that frame.
- 10 13. In or for a typographical composing machine adapted to be equipped with matrix magazines with or without matrix releasing escapements, the combination of a plurality of base frames whereon the magazines of either kind may 15 be removably supported, and means for shifting the base frames to bring any selected magazine into operative position, each of said base frames being provided with a bank of escapements to cooperate with magazines devoid of escapements 20 together with a bank of escapement actuating elements to cooperate with magazines carrying escapements.
14. In or for a typographical composing machine adapted to be equipped with matrix magazines provided with longitudinally extending 25 guide bars of different widths, a supporting frame common to both kinds of magazines and formed with a guideway to receive the guide bar of the magazine in use, said guideway being adjustable 30 in width to accord with that of said guide bar.
15. In or for a typographical composing machine adapted to be equipped with matrix magazines provided with longitudinally extending guide bars of different widths, a supporting frame 35 common to both kinds of magazines and formed with a guideway to receive the guide bar of the magazine in use, said guideway being in the form of a groove having retractable lugs lying part way across the groove.
- 40 16. In or for a typographical composing machine adapted to be equipped with magazines provided with differently located cross bars, a supporting frame common to both kinds of magazines and formed with differently positioned shoulders 45
- to engage the cross bars of one kind of magazine or the other according to the one in use.
17. In or for a typographical composing machine adapted to be equipped with magazines provided with differently located cross bars, a supporting frame common to both kinds of magazines and formed with a stationary shoulder arranged to engage the cross bar of one kind of magazine and with a retractable shoulder to engage the cross bar of the other kind of magazine. 80
18. In or for a typographical composing machine adapted to be equipped with matrix magazines formed with grooved channels arranged at different relative converging angles, the combination of a partitioned assembler entrance to cooperate with either kind of magazine, and a grooved member interposed between the assembler entrance and the magazine in use and having its grooves registering with those of the magazine, those grooves of said member which register with magazine grooves having different angles of convergence being disposed at angles representing the mean of said different angles. 85
19. In or for a typographical composing machine, the combination of two matrix magazines 100 formed with grooved channels arranged at different relative converging angles, a common partitioned assembler entrance, means for bringing either selected magazine into operative relation to the assembler entrance, and a grooved 105 member interposed between the assembler entrance and the magazine in use and having its grooves registering with those of the magazine, those grooves of said member which register with magazine grooves having different angles of convergence 110 being disposed at angles representing the mean of said different angles.
20. A combination according to claim 18, characterized by the fact that the grooved member therein referred to has its grooves flared at their 115 upper ends to provide clearance for the matrices as they pass from the magazine onto the grooved member.
